HOOD FOR SNOWMOBILE

William G. Ness, Thief River Falls, Minn., assignor to Arctic Enterprises, Inc., Thief River Falls, Minn.

Filed Feb. 13, 1970, Ser. No. 21,528

Term of patent 14 years

Int. Cl. D12—13

U.S. Cl. D14—24

*Fig. 4.Fig. 5.FIG. 1 is a front perspective view of a hood for a snowmobile showing my new design;

FIG. 2 is a side elevational view thereof;

FIG. 3 is a front elevational view thereof;

FIG. 4 is a top plan view thereof; and

FIG. 5 is a rear elevational view thereof.

The snowmobile shown in broken lines in FIGS. 1, 2 and 3 is included for illustrative purposes only.

I claim:

The ornamental design for a hood for snowmobile, as shown and described.
